UNITED STATES PATENT OFFICE.

ALEXANDER S. SPEER, OF BUFFALO, NEW YORK, ASSIGNOR, BY MESNE ASSIGNMENTS,
TO CERTAIN-TEED PRODUCTS CORPORATION.

MANUFACTURE OF SHINGLES.

Application filed February 13, 1922, Serial No. 536,282. Renewed August 10, 1927.

This invention relates to the manufacture of shingles for roofing and the like, and aims to provide a novel and improved method and scheme for the manufacture of shingles.

5 The invention consists in the novel constructions and methods, hereinafter described or claimed, for accomplishing the above stated object and such other objects as will appear from the following description.

10 The nature of the invention will be best understood by reference to one illustrative construction embodying the invention and shown in the accompanying drawings.

In said drawings:

15 Fig. 1 is a plan view showing the appearance of a portion of a roof when laid with the illustrative form of shingle.

Figs. 2 and 3 are plan and perspective views, respectively, illustrating a convenient 20 mode of packaging the shingles.

Fig. 4 is a plan view, partly diagrammatic, illustrating a machine and a method of forming the shingles.

Fig. 5 is a side elevation, partly diagrammatic, of the machine shown in Fig. 4.

In the drawings, 10 designates a shingle formed with what may be termed for convenience semi-hexagonal projections 11, extending in opposite directions from opposite 30 sides of the body 12 of the shingle. The body of the shingle is formed so as to extend, as at 13, beyond one side of the projections 11 respectively. When the shingles are laid in courses 14 (see Fig. 1), the extensions 13 separate the adjacent projections 11 by spaces 15. Preferably, the projections 11 have tapering or converging sides 16 so that the ends are of less width than the base thereof. When the courses 14 are laid in over- 35lapping relation and staggered (see Fig. 1) so that the ends 16 of the projections of one course register with the bases of the recesses 15 of the adjacent lower course, the roofing so laid presents the appearance of a plurality of hexagonal shingles. Hence the term "semi- 40hexagonal" has been employed to designate the shape of the tab in the illustrative shingle. Variations in the shape of the shingle projections 11 would produce correspondingly different effects in the appearance of the 45 shingles in a roof.

The side edges 17 of the body 12 of the shingle preferably are straight and form

straight line extensions or continuations of the diagonally opposite edges 16 of the projections 11.

It will be noted by referring to Fig. 1 that the spaces 15 are equal in shape to the projections 11 along the opposite edge of a course 14. It follows, therefore, that the outlines 18 along the upper and lower edges of a shingle are identical and, accordingly, imaginary lines connecting corresponding points on the upper and lower edges 18, and parallel to the diagonal side edges 17, are equal in length throughout the shingle. In

the particular illustrative shingle shown in the drawings, the projections 11 are of equal size and shape and it follows, therefore, that the spaces 15 between adjacent projections 11 along one edge of a course are equal in shape and complementary to projections 15 along this edge. A variation between the shapes of the projections on the upper and lower edge of the shingle will produce a corresponding difference in shape between the spaces and projections along one edge of a course.

70 Preferably, the depth, a of the body 12 of the shingle slightly exceeds the depth b of a tab in order to improve the protection given to a roof when shingles are laid in the manner shown in Fig. 1. This excess of

75 depth of the body of the shingle over that of the projection assists in increasing the protection to the roof by covering the roof for a distance c beyond the base of the corresponding projection 11. Assuming that in a driving rain the wind were sufficient to raise a projection 11 and bend it at its base along the line 19, the roof would nevertheless, be 80 protected against leakage by a shingle layer of the depth c . It is obvious, however, that if it is desired to sacrifice this additional protection c , the depth a of the body of the shingle may be made equal to that of the depth b of a projection. In this case, the upper edge of the underlying courses of the shingles would exactly coincide with the base 85 19 of the overlying tab 11.

90 It will also be observed that the diagonal lines of juncture 20 between adjacent shingles occur in the regions covered by the upper projections 11 of the shingles of the next lower course. This provides protection 95 against leakage along these lines of juncture 100 in case a driving rain should raise the ex-

posed shingle projections sufficiently to creep under the same. It will be observed further that with the particular arrangement of the shingles and courses illustrated in Fig. 1, the 5 roof is covered with at least a double thickness of shingles except in the elongated hexagonal areas 21, in which areas the roof is covered only with a single thickness of shingle. These regions of single thickness 10 occur, however, substantially in the center of each shingle, and in order for leakage to occur in these regions, it would be necessary for moisture to creep from the lower edge 18 of a shingle to the center of the shingle. 15 This could take place only by the raising of a shingle projection and by driving moisture across the protective belt *c* of the underlying shingle. In laying the roof it is desirable to secure the shingles in place by nails placed 20 at 22 and 23 along the base of the recesses 15 and 24 near the opposite edge of the shingle. The securing of the shingle by nails along the base of the recess prevents the raising of this portion of the shingle by 25 driving rain and accordingly prevents moisture from creeping under this portion of the shingle and causing leakage. It is apparent, therefore, that the area 21 of single thickness is amply protected, and with an unusual 30 margin of safety, against leakage by driving rain.

In Figs. 4 and 5 is illustrated a method of and machines for making the shingles heretofore described. The shingles may be 35 cut from any suitable roofing material such as the conventional asphalt, or composition roofing. This roofing is supplied in wide sheets 25 of indefinite length. In order to avoid waste, the individual shingles 10 are 40 cut bias of the sheet with the straight edges 17 parallel with the side edges of the sheet. The edges 18 comprising the end and one side of a shingle projection lie obliquely or diagonally of the sheet 25. In Fig. 4 is illustrated in dotted lines the positions occupied 45 by the respective shingles before the same are cut from the sheet. It is preferable to employ a sheet of sufficient width to form a plurality of shingles arranged side by side, 50 as shown. Although shingles could be formed from a strip of material of a width *d* corresponding to one dimension of the shingle, it is obviously not economical, ordinarily, to make shingles in this way. Preferably, the width of the sheet is a multiple 55 of the dimension "*d*."

In forming the shingles, the sheet of roofing is cut longitudinally along parallel lines 26 to form a plurality of strips 18 of a width 60 *d*. The oblique lines of severance forming the edges 18 of the shingles are so arranged that in each transverse row 27 of shingles, they lie in a region 28, transversely of the sheet, which is less oblique than the obliquity 65 of the individual lines 18. The purpose of

this arrangement will be hereinafter explained. In the particular arrangement shown in dotted lines in Fig. 4, the region 28 lies substantially at right angles to the length of the sheet 25.

Also in Fig. 4 and in Fig. 5 is illustrated, somewhat diagrammatically, a machine for forming the shingles in accordance with the method described above. In general the machine comprises a table or bed 29 for supporting the sheet of roofing. The bed is interrupted at 30 to receive upper and lower feeding rolls 31 for feeding the roofing at a uniform rate to the cutting mechanism hereinafter described. The table is further interrupted at 32 to receive upper and lower for slitting the roofing longitudinally along the lines 26. Such a slitting device may comprise, for example, cooperating pairs of upper and lower slitting knives 33 arranged 75 on a shaft 34, so as to cut the roof as described. These slitters overlap slightly for this purpose. Suitable means, not shown, are provided for rotating the upper and lower shafts 34.

The end of the table 29 is provided with a stationary shear block 35 having a shearing edge conforming in contour to the oblique lines of severance of the individual shingles. Each oblique cutting edge 36 is 80 arranged with respect to the other oblique cutting edges so that they lie in a region which is less oblique to the sheet 25 than the obliquity of the individual cutting edges 36. Mounted beyond the stationary shear 100 block 35 is a movable cutting device 37 having cutting edges 38. In the form of machine illustrated, the cutting device 37 comprises a rotary member adapted to rotate in a clockwise direction, as viewed in Fig. 5, 105 about a shaft 39. The cutting edges 38 are arranged substantially radially of the member 37 and are adapted when rotated to shear the sheet of roofing in cooperation with the stationary shear blade 35. In order 110 to minimize the expenditure of power during the shearing operation, the leading edge 40 of the cutter is arranged to strike the sheet at a slight angle to the bed of the machine (see Fig. 5) so as to effect a gradual shearing of the sheet. Below the cutter a movable conveyor belt 41 is placed for conveying away the shingles as they are severed by the cutter.

The cutter is rotated by suitable mechanism, not shown, and the feeding rolls 31 are driven at such a speed relative to that of the cutter as to feed forward a strip of roofing corresponding to the distance *e* between adjacent rows of oblique lines of severance. By employing the method of cutting the shingles described above, the feeding rolls 31 may be located sufficiently close to the shearing edges of the shear block 35 to avoid any buckling or other dis- 115 120 125 130

placement of the roofing sheet between the feeding rolls and the cutting edge.

Although the individual oblique lines of severance are arranged at a considerable angle to the length of the sheet (the angle of the extremities of these lines of severance being 45 degrees to the length of the sheet), they are arranged relative to each other so that the general direction of the cutting edge of the rotary cutter is not substantially oblique to the sheet. The general obliquity of the cutting edge of the cutter may be arranged at any desired angle to the length of the sheet by positioning the individual oblique lines of severance of each shingle in such a way that they are offset from those of adjacent shingles. In the illustrative arrangement shown in Fig. 4, the general line of the edge of the cutter is at right angles to the length of the sheet. Heretofore in cutting shingles obliquely of the length of the sheet, considerable difficulty has been experienced by the displacement of the roofing due to the relatively extreme angle at which it was severed by the cutter. This difficulty has been further aggravated by the fact that the feeding rolls could not be placed sufficiently close to all points of the cutting edge of the stationary shear block to prevent buckling of the roofing sheet. The roofing sheet is flexible and frequently soft, especially if it has just been made, and tends to buckle beyond the feeding rolls when there is too great a distance between these rolls and the cutter. These difficulties are avoided by staggering or offsetting the individual oblique lines of severance so as to permit the cutting of the sheet transversely along a line which is generally less oblique than the individual lines of severance.

It will be observed that by cutting the shingles bias of the sheet along lines which form the edge of the shingle, in the manner shown, all waste is avoided.

It is obvious that the configuration of the shingle tabs may be varied considerably without departing from the principles of the invention.

Obviously the invention is not limited to any particular form of construction, and the details of the illustrative construction may be variously modified. Moreover, it is not indispensable that all the features of the invention be used conjointly; they may be used to advantage in various different combinations and sub-combinations.

I claim:

1. The method of making individual shingles of the type described from sheet roofing material which comprises slitting the sheet longitudinally into a number of strips of a width corresponding to one dimension of the individual shingles to be cut, and then severing each strip transversely

at intervals along a line extending from edge to edge of said strip, part of which is oblique to the length of the sheet and forms the lower edge of the shingle.

2. The method of making from sheet roofing material individual shingles having inclined sides which comprises slitting the sheet longitudinally into a number of strips of a width corresponding to one dimension of the individual shingles to be cut, and then severing each strip at intervals along the lines which run generally obliquely of the strip and which have the contour of the front or exposed edge of the shingle,—whereby when said shingles are laid in courses, the side edges thereof are inclined to the general line of the course.

3. The method of making individual shingles of the type described from sheet roofing material which comprises slitting the sheet longitudinally into a number of strips of a width corresponding to one dimension of the individual shingle to be cut, and then severing each strip at intervals along lines which run generally obliquely of the strip, said lines connected by a line substantially at right angles to the length of said sheet.

4. The method of making individual shingles having projecting tabs from sheet roofing material which comprises slitting the sheet longitudinally into a number of strips of a width corresponding to one dimension of the individual shingles to be cut, and then severing each strip at intervals along lines which run generally obliquely of the strip, said lines of severance forming the end and one side of the shingle tab and the lines along which said sheet is slit forming the other side of the shingle tab.

5. The method of simultaneously forming a plurality of individual shingles having tabs adapted to be exposed in a roof, which comprises slitting a sheet of roofing material longitudinally into a plurality of strips of a width corresponding to one dimension of the shingle, and severing each strip transversely along a line, generally oblique to the strip, said lines of severance lying in a region of said sheet which extends substantially at right angles to the length of said sheet, and repeating the severing operation at regular intervals along said strips.

6. The method of simultaneously forming a plurality of individual shingles having tabs adapted, when laid in a roof, to simulate hexagonal shingles, which comprises slitting a sheet of roofing material longitudinally into a plurality of strips of a width corresponding to one dimension of the shingle, and severing each strip along a line which forms the end and one side of the tab, said lines of severance lying in a region of said sheet which extends substantially at right angles to the length of said sheet.

tially at right angles to the length thereof and repeating the severing operation at regular intervals along said strips.

7. The method of simultaneously forming a plurality of individual shingles having tabs adapted to be exposed in a roof, which comprises slitting a sheet of roofing material longitudinally into a plurality of strips of a width corresponding to one dimension of the shingle, and severing each strip transversely along a line, the terminal portions of which extend obliquely to the strip, one end of said line and the intermediate portion thereof forming the end and one side, respectively, of the tab, and repeating the severing operation at regular intervals along said strips.

8. The method of simultaneously forming a plurality of individual shingles having tabs adapted to be exposed in a roof, which comprises slitting a sheet of roofing material longitudinally into a plurality of strips of a width corresponding to one dimension of the shingle, and severing each strip transversely along a line, the terminal portions of which are parallel and extend obliquely to the strip, one end of said line and the intermediate portion thereof forming the end and one side, respectively, of the tab, and repeating the severing operation at regular intervals along said strips.

9. The method of simultaneously forming a plurality of individual shingles having tabs adapted to be exposed in a roof, which comprises slitting a sheet of roofing material longitudinally into a plurality of strips of a width corresponding to one dimension of the shingle, and severing each strip transversely along a line, the terminal portions of which are parallel and extend at substantially 45 degrees to the strip, one end of said line and the intermediate portion thereof forming the end and one side, respectively, of the tab, and repeating the severing operation at regular intervals along said strips.

10. The method of simultaneously forming a plurality of individual shingles having tabs adapted to be exposed in a roof, which comprises slitting a sheet of roofing material longitudinally into a plurality of strips of a width corresponding to one dimension of the shingle, and severing each strip transversely along a line, the terminal portions of which are parallel and extend at substantially 45 degrees to the strip, and the intermediate portion thereof extending at 90 degrees to the length of said strip, said portions being of equal length, and repeating said severing operation at regular intervals along said strips.

11. The method of simultaneously forming a plurality of individual shingles having tabs adapted to be exposed in a roof, which comprises slitting a sheet of roofing mate-

rial longitudinally into a plurality of strips of a width corresponding to one dimension of the shingle, and severing each strip transversely along a line, the terminal portions of which are parallel and extend at substantially 45 degrees to the strip, and the intermediate portion thereof extending at 90 degrees to the length of said strip, said portions being of equal length, and repeating said severing operation along said strip at intervals equal to the width of a strip.

12. The method of making bias cut shingles which, when laid in courses on a roof, present the appearance of a plurality of spaced shingle tabs, which comprises providing a sheet of roofing material of a width to provide a plurality of shingles, and severing said sheet at intervals transversely to form the outlines of one side of the shingles, the outlines of the individual shingles in the sheet being offset relative to the position occupied when the shingles are laid adjacent to each other in the roof, said offset lines of severance permitting said sheet to be cut along a line running generally at right angles to the length of the sheet, and cutting said sheet longitudinally to divide the transversely severed portion into said plurality of individual shingles.

13. The method of making simultaneously a plurality of shingles cut on the bias of a sheet of roofing material, which consists in severing a sheet of roofing at intervals, transversely, along lines forming the outlines of the ends and one side of a plurality of shingles, the lines of severance being so arranged relatively to one another that said outlines of the individual shingles are offset relative to the position occupied by such outlines when the shingles are laid in courses on a roof, such arrangement permitting said sheet to be severed transversely along a line, the general direction of which is substantially at right angles to the length of the sheet and cutting said sheet longitudinally to divide the same into said plurality of individual shingles.

14. The method of making simultaneously a plurality of shingles cut on the bias of a sheet of roofing material, which consists in severing a sheet or roofing at intervals, obliquely, along lines forming the outlines of the ends and one side of a plurality of shingles, the lines of severance being so arranged relatively to one another that said outlines of the individual shingles are offset relative to the position occupied by such outlines when the shingles are laid in courses on a roof, such arrangement permitting said sheet to be severed transversely along a line, the general direction of which is less oblique than the obliquity of the individual shingles relative to the sheet, and cutting said sheet longitudinally to divide the same into said plurality of individual shingles.

15. Apparatus for making bias-cut shingles of the type described, comprising in combination, means for feeding a sheet of roofing material, a cutting device across the path of said material and adapted to sever said material transversely at intervals along a line, the general direction of which is less oblique than the obliquity of the cut of the individual shingles, said cutting device provided with a cutting edge adapted to cut said material to form the end and one side of a plurality of shingles, and means for cutting said material longitudinally to form the other side of said shingles.
15. 16. Apparatus for making bias-cut shingles of the type described, comprising in combination, means for feeding a sheet of roofing material, a rotary cutter adapted to sever said material transversely at intervals, said cutter provided with a cutting edge adapted to form the front edge and one side of a plurality of shingles, said front edges being cut obliquely to the sheet of material, the axis of said cutter being arranged transversely of said sheet at an angle less oblique than that of the front edges of said shingles, and means for cutting said sheet longitudinally to form the other sides of said shingles.
17. Apparatus for making bias-cut shingles of the type described, comprising in combination, means for feeding a sheet of roofing material, a rotary cutter adapted to sever said material transversely at intervals, said cutter provided with a cutting edge adapted to form the front edge and one side of a plurality of shingles, said front edges being cut obliquely to the sheet of material, the axis of said cutter being arranged substantially at right angles to the direction of feed of said sheet, and means for cutting said sheet longitudinally to form the other sides of said shingles.
18. Apparatus for making bias-cut shingles of the type described, comprising in combination, means for feeding a sheet of roofing material, a rotary cutter adapted to sever said material transversely at intervals, said cutter provided with a cutting edge adapted to form the front edge and one side of a plurality of shingles, said front edges being cut obliquely to the sheet of material, said cutting edge as a whole being arranged relative to the direction of feed at an angle less oblique than the obliquity of the individual shingles, and slitting cutters adapted to slit said sheet longitudinally between the shingles.
19. Apparatus for making bias-cut shingles of the type described, comprising in combination, means for feeding a sheet of material, slitting devices for slitting said sheet longitudinally into a plurality of strips of a width corresponding to one dimension of the shingle, a rotary cutter having a cutting edge for severing said sheet transversely at intervals along a line forming, on each of the strips, the front edge and one side of a shingle, the axis of said cutter being at right angles to the direction of feed, and corresponding parts of said cutting edge being substantially the same distance from said axis, and a stationary cutting blade adapted to cooperate with said rotary cutter.
20. Apparatus for making shingles of the character described, comprising in combination, means for feeding a sheet of roofing material, slitting devices for slitting said sheet longitudinally into a plurality of strips of a width corresponding to one dimension of said shingle, a periodically operating cutter having cutting edges for severing said strips transversely at intervals along lines forming the front edge and one side of the exposed portion of said shingle, the cutting edges of said cutter being arranged to lie in a line substantially at right angles to the direction of travel of said sheet with corresponding parts of said cutting edges lying substantially in lines at right angles to the direction of travel of said sheet, and a stationary cutting blade arranged to cooperate with said cutter.

In testimony whereof, I have signed my name to this specification.

ALEXANDER S. SPEER.
